(12) **United States Design Patent** (10) **Patent No.:** **US D893,843 S**
Hartmann (45) **Date of Patent:** **** Aug. 25, 2020**

(54) **SHOE**
(71) Applicant: **PUMA SE**, Herzogenaurach (DE)
(72) Inventor: **Matthias Hartmann**, Forchheim (DE)
(73) Assignee: **PUMA SE**, Herzogenaurach (DE)
(**) Term: **15 Years**
(21) Appl. No.: **29/667,516**
(22) Filed: **Oct. 23, 2018**
